PYROMETER.

1,205,825.

Specification of Letters Patent. Patented Nov. 21, 1916.

Application filed December 19, 1912. Serial No. 737,640.

To all whom it may concern:

Be it known that I, EMERSON L. CLARK, a citizen of the United States, residing at Lakewood, in the county of Cuyahoga and 5 State of Ohio, have invented a certain new and useful Improvement in Pyrometers, of which the following is a full, clear, and exact description.

My invention relates to pyrometer systems and provides means for correcting inaccuracies due to change in temperature of cold junctions in the thermopile.

In thermopiles the "cold junctions" generate E. M. F.'s but in a direction opposed 10 to the E. M. F. of the hot junction. The E. M. F. impressed on the galvanometer is therefore less than that of the hot junction. Consequently allowance must be made for the E. M. F. of the cold junctions in using 15 the thermopile to determine temperatures. If the temperature of the "cold junctions" is maintained constant the correction would be a simple matter as the galvanometer would be calibrated for the drop in E. M. F. 20 caused by the counter E. M. F. However, the temperature of the "cold junctions" cannot easily be maintained constant in practice. It is therefore necessary to provide means to compensate for such change in the 25 temperature.

The manner in which the compensation is accomplished will be apparent from the following description, reference being had to the drawings in which.

Figure 1 is a modified form of compensating system. Fig. 2 diagrammatically illustrates the circuits of the system shown in Fig. 1. Fig. 3 is another modification of a compensating system. Fig. 4 is a diagrammatic arrangement of the circuits of the system shown in Fig. 3.

Referring to Fig. 1, the thermopile here illustrated has a hot junction 1 and cold junctions 2 and 3. The cold junction 3 is connected directly to the terminal 4 of a galvanometer. The junction 2 is connected through resistance r^4 and a source of E. M. F. 5 to a point 8. A compensating coil r^1 has one terminal connected to the cold junction 2 and the other one to the point 8. Here the circuit divides in two branches, one extending through a source of E. M. F. 10, resistance r^5 to a point 10, and the other through resistance r^2 to the point 10. The point 10 is connected to the terminal 5 of

the galvanometer. The compensating coil r^1 is wound around, or otherwise arranged in close proximity to the cold junction so that it will be subjected to the same temperature. This resistance, of course, would be properly insulated so that no contacts would be made at other points than those indicated.

The circuits are shown more diagrammatically in Fig. 2. The sources of E. M. F. 15 and 9 may be one or more dry cells, for instance. However, any other source of E. M. F. that has a substantially constant voltage may be used. The sources 6 and 9 are connected as shown with the positive 20 poles joined together. The thermocouple 1 is so arranged that its positive terminal is connected to the negative terminal of the resistance r^4 . The system at a certain temperature, say 24 degrees would preferably be 25 arranged so that the voltage of 6 would substantially equal the voltage of 9, the resistance of r^5 would substantially equal r^4 and the resistance of r^2 would substantially 30 equal r^1 . The resistances r^4 and r^5 would be large compared to the resistances r^1 and r^2 .

If the temperature of the cold junction were 24 degrees and the temperature of the hot junction also 24 degrees there would be 35 current flowing through the galvanometer G, since the drop of E. M. F. from 7 to 8 is the same as from 10 to 8. In other words the potential of point 7 would be the same as point 10. Current, however, would be flowing through the battery 6, resistances 40 r^4 and r^5 as indicated by the arrows. Current would also be flowing through battery 9, resistances r^2 and r^1 as indicated. Then if the temperature of the cold junctions remain still at 24 degrees and the temperature 45 of the hot junction be raised to some temperature, say 900 degrees, the E. M. F. generated at the hot junction would send a current through resistance r^4 , battery 6, resistance r^5 and the galvanometer G. The galvanometer would be so calibrated that it would indicate the voltage or temperature at the hot junction 1 with the resistances arranged as shown. If, however, the cold junctions also increase in temperature the 50 resultant voltage produced by the thermopile would be reduced due to the increase in the bucking E. M. F. of the cold junctions. The increase in temperature of the cold junctions, however, increases the resist- 55

100
105
110

ance r^4 since it has a positive temperature coefficient of resistance. This increase in resistance of coil r^4 cuts down the current drawn from battery 6. The decrease of current decreases the drop in the line resistance r^1 and therefore raises the voltage between the points 7 and 8. The voltage between the points 10 and 8 has not been changed since the coils have not changed in resistance. Then by using a resistance r^1 of suitable value and of suitable positive temperature coefficient, this rise in voltage between points 7 and 8 may be made to substantially equal the decrease in voltage of the thermocouple due to increased cold junction temperature. The voltage around the circuit r^4 , battery 6, r^2 , galvanometer G and the thermocouple therefore remains the same. The reading will therefore be the same regardless of the increase of temperature in the cold junctions.

If the cold junction temperature drops below 24 degrees and the hot junction remains at 900 degrees the resultant E. M. F. of the thermocouple would be increased and if there were no compensating arrangement the galvanometer would indicate a greater voltage or temperature than actually existed at the hot junction. However, with the compensating system shown a decrease in temperature at the cold junctions also means a decrease of resistance of the coil r^4 . This decrease in the resistance causes an increase in the current drawn from the battery 6 which may be traced through point 8, resistance r^1 , point 7, back to the battery 6. The increase of current through resistance r^1 increases the drop therein and hence decreases the voltage applied to the coil r^4 . Thus the potential between the points 8 and 7 has been diminished. This decrease of potential equals the increase in voltage of the thermocouple, so that the voltage around the circuit r^4 , battery 6, r^2 , galvanometer G and thermocouple 1 remains the same. The reading of the galvanometer will therefore be correct regardless of the decrease in the temperature of the cold junctions.

In Fig. 4 the circuits are arranged similarly to those in Fig. 2 with the exception of the location of the thermocouple. This is placed directly in circuit between the points 7 and 8 with its positive terminal connected to the conductor leading to the point 8.

Suppose that the hot junctions and cold junctions are at the same temperature, for example 24 degrees. The potential of point 10 would be the same as the potential of point 7 and no current would flow through the galvanometer. Current, however, would flow from battery 6 to point 8 through the thermocouple, resistance r^2 to point 7 and back through resistance r^4 to the battery. Current would also flow from battery 9 to

point 8 through resistance r^2 to point 10 and back through resistance r^5 to the battery. If now the hot junction be raised to a temperature, say 900 degrees, the E. M. F. of the thermocouple will be increased. The increase of E. M. F. would raise the potential between the points 8 and 7. The points 10 and 7 are therefore at different potentials and current will flow from battery 6 through point 8, resistance r^2 , galvanometer G, point 7 and resistance r^4 back to the battery. This will give the correct indication on the galvanometer of the temperature at the hot junction of the thermocouple. If now the cold junction temperature rises while the hot junction temperature remains at 900 degrees the resultant E. M. F. of the thermocouple is less than before, and there would be a tendency for the galvanometer to indicate less than the true temperature of the hot junction. However, the increase of temperature at the cold junction causes an increase in resistance of r^4 , which diminishes the current flowing through the shunt circuit containing resistance r^1 , resistance r^3 and battery 6. The drop in r^1 is therefore decreased and the potential between the points 7 and 8 is accordingly increased. By choosing the proper values for the resistances the increase in resistance in r^4 may be made to bring the difference of potential between the points 2 and 8 back to what it was before the temperature of the cold junctions increased and the galvanometer indication will be maintained correct.

If the temperature of the cold junctions should drop below, say 24 degrees, the resultant E. M. F. of the thermocouple would increase and there would be a tendency for the galvanometer to indicate a higher temperature than existed at the hot junction 1. A decrease in temperature of the cold junctions, however, causes a decrease in the resistance r^4 . The current through battery 6, resistance r^1 and resistance r^4 is therefore increased. This increase of current causes a greater drop in the high resistance r^4 , and lowers the difference of potential between the points 2 and 8. The voltage between these two points is therefore brought back to the same value as before the cold junction temperature decreased and the reading of the galvanometer is brought back to the correct value.

The resistances r^2 , r^3 , r^4 and r^5 in all the systems disclosed herein would be made of metal that has a negligible temperature coefficient, many of which are to be found on the market. When the systems shown in Figs. 1 and 2 have been properly arranged the compensation is correct within a fraction of a per cent. for a wide range of hot junction temperatures, and therefore when the system is once set, no change of resistances will be necessary.

The system shown in Fig. 3 has the advantage over that shown in Fig. 1 of requiring only two leads from the thermocouple to the galvanometer system, while that in Fig. 2 requires three wires. This advantage, however, is small as there is no serious objection to using three wires between the thermocouple and the galvanometer system. The system shown in Fig. 1 has the advantage over that shown in Fig. 3 in that the thermocouple circuit may be opened without throwing the high voltage of the batteries directly on the galvanometer.

Having described my invention what I claim is:

1. In a pyrometer system, a galvanometer, a thermocouple, a resistance having a positive temperature coefficient located closely adjacent the cold junction of said thermocouple, a second resistance, said resistances being connected together at one end and being connected together at their other ends through the thermocouple and galvanometer, and a source of E. M. F. in a circuit connected in parallel to each of said resistances.
2. In a pyrometer system, a galvanometer, a circuit connected thereto containing a thermocouple and a resistance having a positive temperature coefficient located closely adjacent the cold junction of said thermocouple, and a circuit in parallel to a part of said first mentioned circuit containing a source of E. M. F.
3. In a pyrometer system, a galvanometer, a circuit connected thereto containing a thermocouple and a resistance having a positive temperature coefficient located closely adjacent the cold junction of said thermocouple, and a circuit in parallel to a part of said first mentioned circuit containing a source of E. M. F. and a resistance.
4. In a pyrometer system, a galvanometer, a circuit connected thereto containing a thermocouple and a resistance having a positive temperature coefficient located closely adjacent of the cold junction of said thermocou-

ple, and a circuit in parallel to said resistance containing a source of E. M. F.

5. In a pyrometer system, a galvanometer, a thermocouple, a resistance having a positive temperature coefficient located closely adjacent the cold junction of said thermocouple, a second resistance, said resistances, galvanometer and thermocouple being connected in series in a closed circuit, and a circuit consisting of a source of E. M. F. and a resistance connected in parallel to the circuit containing each of said resistances.

6. In a pyrometer system, a circuit containing a galvanometer, a thermocouple and a resistance having a positive temperature coefficient, said resistance being located adjacent the cold junction of the thermocouple and a shunt circuit around said resistance containing a source of E. M. F. and a second resistance.

7. In a pyrometer system, a galvanometer, a thermocouple, a resistance of substantially constant value, a second resistance of positive temperature coefficient located closely adjacent the cold junction of said thermocouple, said resistances and thermocouple being connected in series to the terminals of said galvanometer, and a shunt circuit around said second resistance containing a source of E. M. F. and a third resistance.

8. In a pyrometer system, a galvanometer, a thermocouple, a resistance of substantially constant value, a second resistance of positive temperature coefficient located closely adjacent the cold junction of said thermocouple, said resistances and thermocouple being connected in series to the terminals of said galvanometer, and a shunt circuit around said first mentioned constant resistance containing a source of E. M. F. and a third resistance.

In testimony whereof, I hereunto affix my signature.
